UNITED STATES PATENT OFFICE.

HENRY EBERLY HIBSHMAN, OF NEWARK, NEW JERSEY, ASSIGNOR TO
CLARENCE JAMES McCUAIG, OF MONTREAL, CANADA.

MUSICAL INSTRUMENT.

SPECIFICATION forming part of Letters Patent No. 744,546, dated November 17, 1903.

Application filed March 6, 1903. Serial No. 146,501. (No model.)

To all whom it may concern:

Be it known that I, HENRY EBERLY HIBSHMAN, a citizen of the United States, and a resident of Newark, in the county of Essex and State of New Jersey, have invented a new and Improved Musical Instrument, of which the following is a full, clear, and exact description.

The invention relates to reed instruments of the mouth-harmonica type; and its object is to provide a new and improved musical instrument which is simple and durable in construction and arranged to enable a person to properly execute a piece of music with the aid of a perforated music-sheet without requiring practice or knowledge of music.

The invention consists of novel features and parts and combinations of the same, as will be more fully described hereinafter and then pointed out in the claims.

A practical embodiment of the invention is represented in the accompanying drawings, forming a part of this specification, in which similar characters of reference indicate corresponding parts in all the views.

Figure 1 is a perspective view of the improvement. Fig. 2 is a front elevation of the same, showing the cover open and parts in section. Fig. 3 is a transverse section of the improvement on the line 3 3 of Fig. 2, and Fig. 4 is a sectional plan view of the same on the line 4 4 of Fig. 3.

The musical instrument is mounted in a suitably-constructed casing A, having a perforated back A', a hinged cover B at the front, and a handle C at the bottom for the operator to conveniently take hold of and properly support the casing by the use of one hand.

Within the casing A is secured a horizontally-disposed reed-block D, having suitable reeds preferably arranged in chromatic or other scale, and the mouth of the said reed-block D forms a tracker-board for the passage of a perforated music-sheet E, unwinding from a drum F and winding up on a drum G, as plainly indicated in Fig. 3. The drums F and G are located on opposite sides of the reed-block D, and are arranged relative to the tracker-board, so that the music-sheet E is firmly stretched over the tracker-board at the time the music-sheet is wound up on the

drum G and unwound from the drum F. The drums F and G rotate in unison, and for this purpose gear-wheels H and H' are provided, rotating with the drums and in mesh with each other, and the shaft G' of the drum G extends to one side of the casing A and is provided at its outer end with a removable crank-arm I, under the control of the operator, so that when the crank-arm I is turned both drums G and F are rotated in unison for causing the music-sheet to travel over the tracker-board, as above explained.

The front face of the cover B is formed into a mouthpiece B', from which leads the narrow opening B² of an air-passage, widening on the back of the cover, as at B³, and surrounded by a wall B⁴, projecting from the inner face of the cover B, as plainly indicated in the drawings, the said wall B⁴ being located directly opposite the tracker-board, and the face of the wall is preferably covered with felt or other soft material, so as to engage that portion of the music-sheet E passing over the tracker-board at the time. Now when air is blown by the mouth of the performer through the air-passage, then this air passes through the registering perforations in the music-sheet E into the reed-cells of the reed-block D to sound the reeds therein, it being also understood that on drawing air through the said air-passage the reeds are sounded according to the perforations in the music-sheet registering with corresponding air-cells. Thus by blowing air into or drawing air through the air-passage the corresponding reeds in the reed-block D are sounded, and the music performed corresponds to the music indicated by the perforations in the music-sheet E, caused to travel between the tracker-board and the wall B⁴ by the operator turning the crank-arm I correspondingly. Now, according to the music to be performed, the time may be varied by the operator turning the crank-arm I faster or slower.

In order to permit a convenient interchange of music-sheets E, the drum F is removably mounted in the casing, and for this purpose the shaft J of the gear-wheel H has a square end engaging a corresponding socket in one end of the drum F, and the other end of the

said drum is provided with a fixed trunnion F', pressed on at its outer end by a spring K, attached to the casing at the outside of the bearing for the shaft F' and that of the shaft G'. (See Fig. 2.) Now when it is desired to remove the drum F the operator slides the same to the left against the tension of the spring K until the square end of the shaft J is disengaged from the socket in the drum F to allow the operator to move the drum F from the casing for placing another sheet of music thereon and then reinserting the drum in the casing and connecting it with the shaft J. The outer end of the sheet of music E is then connected with the drum G, to be wound up thereon by the operator turning the crank-arm I, as above explained.

It is understood that by having the face of the wall B' covered with felt or like material air is prevented from being wasted, and consequently it requires but little power on the part of the operator to properly sound the reeds of the reed-board, according to the music to be performed.

25 The shaft J of the gear-wheel H is preferably extended to the outside of the casing and provided with a square terminal for applying the crank-arm I to turn the drum F in a reverse direction whenever it is desired to rewind the music-sheet E on the drum F. In the case described the gear-wheels H H' may be dispensed with, as the crank-arm I may be applied to either shaft G' or J for turning the corresponding drum to wind up the music sheet.

Having thus described my invention, I claim as new and desire to secure by Letters Patent—

1. A musical instrument comprising a reed-block, formed at its mouth with a tracker-board for the passage of a perforated music-sheet, and a mouthpiece fitting onto the music-sheet, directly over the tracker-board, the said mouthpiece having an air-passage 40 which is small at the outer face of the mouthpiece and widens on the inner face, to register with all the cells in the reed-block, as set forth.

2. A musical instrument comprising a reed-block, formed at its mouth with a tracker-board for the passage of a perforated music-sheet, a mouthpiece fitting onto the music-sheet, directly over the tracker-board, the said mouthpiece having an air-passage which

is small at the outer face of the mouthpiece 55 and widens on the inner face, to register with all the cells in the reed-block, and manually-controlled drums for moving the music-sheet over the tracker-board, as set forth.

3. A musical instrument comprising a casing having a perforated back and a cover provided with a mouthpiece formed with an air-passage, narrow at the front face of the cover and gradually widening to the rear thereof, a reed-block secured in the casing and having a tracker-board in alignment with the inner widened portion of the air-passage, drums journaled in the casing on opposite sides of the reed-block, the shaft of one of the drums carrying a crank-arm on the outside of the casing, and gear-wheels on the drum, in mesh with each other, as set forth.

4. A musical instrument comprising a casing having a perforated back and a cover provided with a mouthpiece formed with an air-passage, narrow at the front face of the cover and gradually widening to the rear thereof, the inner widened portion of the air-passage being surrounded by a felted wall, a reed-block secured in the casing and having a tracker-board in alignment with the inner widened portion of the air-passage, drums journaled in the casing on opposite sides of the reed-block, the shaft of one of the drums carrying a crank-arm on the outside of the casing, and gear-wheels on the drum, in mesh with each other, as set forth.

5. A musical instrument comprising a casing having a perforated back and a cover provided with a mouthpiece formed with an air-passage, narrow at the front face of the cover and gradually widening to the rear thereof, a reed-block secured in the casing and having a tracker-board in alignment with the inner widened portion of the air-passage, drums journaled in the casing on opposite sides of the reed-block, the shaft of one of the drums carrying a crank-arm on the outside of the casing, and one of the drums being removably held in the casing, and gear-wheels on the drum, in mesh with each other, as set forth.

In testimony whereof I have signed my name to this specification in the presence of two subscribing witnesses.

HENRY EBERLY HIBSHMAN.
